United States Patent Office.

ADAM SCHWAAB, OF NEW YORK, N. Y.

Letters Patent No. 94,656, dated September 7, 1869.

IMPROVED SOFA-BEDSTEAD.

The Schedule referred to in these Letters Patent and making part of the same

To all whom it may concern:

Be it known that I, ADAM SCHWAAB, of the city, county, and State of New York, have invented a new and improved Sofa-Bedstead; and I do hereby declare that the following is a full, clear, and exact description thereof, which will enable others skilled in the art to make and use the same, reference being had to the accompanying drawing, forming part of this specification.

The object of this invention is to provide a simple and cheap construction of sofas for adaptation, to be used also as bedsteads.

The invention consists of an arrangement, whereby the upholstered part of the back may be swung forward out of the frame on hinged arms, and arranged alongside and in the same horizontal plane with the seat, to form a bed, as hereinafter specified.

Figure 1 represents a front elevation of my improved sofa-bedstead, and

Figure 2 represents a transverse sectional elevation of the same.

Similar letters of reference indicate corresponding parts.

Instead of permanently connecting the upholstered part A of the back to the frame B, I provide a separate frame or back, C, for the same, and joint it at the ends to arms D, journalled to the frame at L, or connected to a transverse shaft, E, journalled at the said point. I also provide upon the back C, near the edge F, which is the lowest when folded up, and the outermost when turned down, to be used as a bed, the folding legs G, which are arranged as represented in red, when used as a bed, and which may be held in the folded-up condition against the back by loops, or any other devices.

The posts H of the frame B are recessed, as shown

at I, for the reception of the arms D, when folded up in the position shown in fig. 1. The arms are shouleder'd at K, to rest on the back-rail L, to support the back when used as a sofa, and the upper edge of the said back rests against the front of the top-rail of the frame B, as shown at M. When turned down, as shown in red, the inner edge of the back is supported by the pivots N, by which the ends are connected to the arms D, and the said arms are supported by resting on the front rail O of the frame of the seat.

Head and foot-boards, P, may be secured at each end by dowel-pins, one at the front entering a hole in the part C, and another at the rear taking into a transverse bar, Q, or by any other suitable or preferred arrangement.

A drawer, R, may be attached to the under side of the seat, to slide in and out, for storing the head and foot-boards, also the bed-clothes, when used as a sofa.

Having thus described my invention, I claim as new, and desire to secure by Letters Patent—

1. The sofa-back A, fitted to the frame B, and jointed upon arms D, arranged for folding it into the said frame or down in front of the seat, and relatively thereto, substantially as specified.
2. The arrangement, with the arms D, of the shaft E and back-rail L, substantially as specified.
3. The arrangement, with the back A, of the hinged legs G and the arms D, when the said arms rest on the rail O, to support the inner part of the bottom, all substantially as specified.

ADAM SCHWAAB.
